United States Patent Office

Des. 183,634
Patented Sept. 30, 1958

183,634

CAP OR THE LIKE

Floyd C. Romeo, Youngstown, Ohio

Application October 2, 1957, Serial No. 47,943

Term of patent 14 years

(Cl. D3—13)

FIG. 1

FIG. 2

FIG. 3

FIG. 4

Figures 1, 2, 3, and 4 are side elevation, top plan, rear elevation, and front elevation, respectively, of a cap showing my new design.

I claim:

The ornamental design for a cap or the like, as shown.
